(57)

CLAIM

The ornamental design for an umbrella base weight bag, as shown and described.

DESCRIPTION

FIG. 1 is a top perspective view of an umbrella base weight bag, according to the present design;

FIG. 2 is a bottom perspective view thereof;

FIG. 3 is a right side view thereof, the left side view being a mirror image thereof;

FIG. 4 is a back side view thereof;

FIG. 5 is a front side view thereof;

FIG. 6 is a top plan view thereof; and,

FIG. 7 is a bottom plan view thereof.

The broken lines depict portions of the article that form no part of the claimed design.

1 Claim, 7 Drawing Sheets
